SHIP

George R. Harrison, Detroit, Mich.

Application April 13, 1944, Serial No. 530,832

4 Claims. (Cl. 114—240)

This invention relates to ships and has for its principal object the provision of a ship which is not only resistant to rolling but is materially more resistant than conventional ship structures to the explosive effects of torpedoes or mines.

Objects of the invention include the provision of a ship, and particularly a ship hull, having a sponson-like structure on either side thereof of new and improved form and construction; the provision of a ship hull having air chambers extending along each side thereof and open to the water along their lower edges; the provision of a ship hull having air chambers extending along each side thereof extending to a point above the water line and extending downwardly therefrom to a point adjacent the bottom of the hull; the provision of a ship hull having a wall spaced outwardly from each side of the buoyant position of the hull and sealed to the hull except along its lower edge at which it is formed to provide open communication of the space between it and the boat hull proper with the water below the water line; the provision of a construction as above described in which the wall members project along the sides of the boat hull for substantially the full distance thereof; and the provision of a construction as above described of novel conformation and secured to the boat hull in a novel manner.

The above being among the objects of the present invention, the same consists of certain novel features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Fig. 1 is a side elevational view of a ship constructed in accordance with the present invention;

Fig. 2 is a broken plan view of the ship shown in Fig. 1;

Fig. 3 is a slightly enlarged stern view of the ship shown in the preceding views, with portions thereof broken away and shown in section to better illustrate the present invention;

Fig. 4 is an enlarged transverse sectional view of that portion of the ship shown in Fig. 3 included within the circle 4 thereof;

Fig. 5 is an enlarged fragmentary, horizontal sectional view, taken on the line 5—5 of Fig. 3; and,

Fig. 6 is an enlarged, fragmentary, vertical sectional view taken on the line 6—6 of Fig. 3.

Because of the wars which we are now being engaged in there is a considerable amount of interest in connection with providing ships with means to prevent, or minimize, damage thereto through being struck by a torpedo or from coming in contact with a mine. In one respect the present invention has a similar object, that is, a construction which will minimize the damage which a ship would otherwise suffer from being struck by a torpedo or from striking a mine.

As far as I am aware, structures heretofore proposed to obtain the above described results includes means added to a conventional ship hull which are substantially useless apart from their intended purpose, and have no other material advantage, otherwise being a useless appendage. The present invention has, in addition to its protective feature above described, an additional advantage which is of material importance regardless of its protection against torpedoes or mines, and this feature is that additionally it provides a means for materially reducing the roll of a ship in a sea and thereby rendering a passenger carrying ship more comfortable for its passengers, a freighter more comfortable for its crew, and it further minimizes the danger of a ship rolling over in a heavy sea.

Broadly, the present invention consists in providing chambers extending along each side of a ship from a point above the normal water line and extending to a point preferably adjacent the bottom of the ship. These chambers are sealed to the ship along their tops and ends but are open to the water along their bottoms. The upper portions thereof will, therefore, always contain a body of air, the lower portions thereof will always contain water. They, therefore, serve to some extent, in the nature of sponsons, but otherwise have an effect that is materially different.

The invention may be applied to ships in a variety of different manners. For instance, a ship may be designed and constructed wherein the chambers of the present invention are provided by double sides, in which case the chambers will normally lie within the lateral confines of the deck and the appearance of the ship will be conventional. On the other hand, the chambers may be formed separately from the ship as separate units and thereafter be removably or permanently secured to the ship in any suitable manner. On the other hand, these chambers may be formed by securing an additional and

outwardly spaced wall to each side of a conventional or existing ship and this last form of construction has been selected for the purpose of illustration in the accompanying drawings.

It will also be appreciated that, broadly, the particular means employed for forming these chambers and securing them in place on a ship may vary to a considerable extent, the particular form of construction shown in the accompanying drawings being preferable and constituting a more limited phase of the present invention.

Referring now to the accompanying drawings, a ship is shown, including a conventional hull illustrated at 10, conventionally provided with a cabin 12, a conventionally supported and driven screw propeller 14 at its stern, and a conventional rudder 16 conventionally mounted and operated. In accordance with the present invention, a chamber 18 is formed along each side of the hull and over substantially the full length thereof. Such chambers, as best brought out in the second sheet of the drawings, are each preferably formed by means of a preferably metallic wall indicated generally at 20 arranged in outwardly spaced relation with respect to each side of the hull 10 and extending from a point above the water line to a point adjacent the bottom of the hull, preferably extending around the bilges to a point preferably below the bottom of the hull, as brought out in Fig. 3. The upper edges of the walls 20 are bent laterally inwardly into contacting relationship with respect to the sides of the hull 10 and are sealed thereto, as are also the forward and rear edges of the walls 20. The bottom of each chamber is in open communication with the water and although this may be accomplished by providing openings in the walls 20 and securing the lower edges of such walls directly to the boat hull 10, in the construction shown the lower edge of each wall 20 is spaced a material distance from the cooperating side or bottom wall of the hull so as to provide an opening of generous proportions affording constant, open and free communication between the interiors of the chambers 18 and the water below the level of the water line.

It will be appreciated from the above that the upper portions of the chambers 18 will always have a material volume of air entrapped therein and the bottom portions of the chambers 18 will be filled with water to a greater or lesser extent. The relative amounts of air and water in each chamber 18 will, of course, vary to a greater or lesser extent due to inevitable leakage of air from the chambers 18 and from variations in amount of air which may inevitably infiltrate through leaks in the walls 20 into the chambers 18, or from the open bottom ends of the chambers being exposed directly to the air when the ship pitches or rolls in heavy sea.

In the particular construction shown, the wall 20 is made up of a plurality of metallic plates such as 20a which are corrugated in the direction of the length of the hull as shown, these corrugations being provided primarily to impart rigidity and stiffness to the wall 20 so as to enable thinner and, therefore, lighter gage of material to be employed therein than would otherwise be possible and still impart the necessary strength to the structure to serve its intended purposes. The corrugations 20a are, of course, extending longitudinally in approximate parallelism with the water line of the ship in order to minimize the drag created by the application of the invention to a ship.

In the particular case shown, the plates 20a are secured and sealed to each other through overlapping marginal edges indicated best at 30 in Fig. 4, which are suitably secured together as by means of welding, as shown, or by any other suitable means. The marginal edges of the walls 20 which are sealed to the hull may be welded thereto, as indicated at 32 in Fig. 4, or otherwise suitably secured thereto.

To further strength the walls 20 it is preferred to extend plates 34, best brought out in Figs. 2 and 5, between each side of the hull 10 and the wall 20 at intervals over the length of the chambers 18, such plates 34 preferably extending from the top to the bottom of such chambers and serving as transverse and preferably water-tight bulkheads dividing each chamber 18 into a plurality of longitudinally separate sub-chambers or compartments. The plates or bulkheads 34 are preferably not arranged in perpendicular relationship with respect to the corresponding side of the hull 10 but rather, and as brought out in Fig. 5, at an angle thereto, this being for the purpose of providing a connection between the sides of the hull 10 and the walls 20 that will more readily yield upon impact or under pressure, or from any other force tending to displace a wall 20 with respect to its corresponding side of the hull 10. The plates or bulkheads 34, even though they are not completely sealed to both the sides of the hull 10 and to the corresponding wall 20, serve to prevent longitudinal surge of water in the chambers 18, and when sealed from each other it will be appreciated that the puncturing of one or more of the compartments formed between them will not destroy the usefulness of the remainder thereof.

Particularly where the provision of the chambers 18 are of importance from the standpoint of protection against torpedoes or mines, it is further desirable to split that portion of each chamber 18 below the water line into two or more thicknesses. In the drawings each chamber 18 is shown as being split up into two thicknesses by means of an intermediate wall 36, shown as being positioned approximately midway between each wall 20 and the cooperating side of the hull 10 and extending from a point above the water line to a point adjacent the bottom of the chamber 18. In the particular case shown, the walls 36 are composed of plates fitting between adjacent plates or bulkheads 34 and sealed at their ends thereto as by means of welding or the like.

From a protection standpoint against torpedoes or mines, it will be appreciated that if a torpedo or mine should strike one of the walls 20 it will be below the water line thereof and in exploding will rupture the wall 20 in the area surrounding the explosion. The explosion will drive the water in the adjacent compartments in each chamber 18 both upwardly and downwardly, and the force of the water being driven upwardly will be cushioned by the air in the upper parts of the chamber 18, and the water which is driven downwardly will be expelled freely out of the open lower end of such chamber. The effect of the displacement of the water in the affected chambers in such case will be to cushion and dissipate the force of the explosion and minimize if not prevent damage to the corresponding side of the boat hull 10. The protective effect of the chambers will be increased according to the number of layers provided therein by means of intermediate walls such as 36 and may be varied to some extent by varying the spacing of the lower edges of the walls 20 from the

hull, or otherwise, so as to vary the resistance to the escape of water from the compartments 18 under such circumstances.

The construction described, however, is believed to have an additional and possibly a more important advantage than the protection afforded as above described, and, as previously suggested, this is in connection with damping the rolling motion of a ship. In this connection, it will be appreciated than in a sea as a wave of water rises on one side of the ship it will tend to lift such side of the ship and depress the opposite side thereof, thereby to produce a roll. Where such ship is constructed in accordance with the present invention, the side of the ship which tends to thus lift tends to carry with it the bulk of the water contained in the chamber 18 in the corresponding side of the ship, thus producing, in effect, an added weight to this side of the ship tending to oppose the rolling action. The air in the chamber 18 on this side of the ship will be trapped in the chamber but will be compressed as the wave rises around it. At the same time, the opposite side of the ship which tends to roll downwardly into the water tends to raise the level of the water in the corresponding chamber 18, this rise in level being resisted by the air in the upper portion of the chamber which, while being somewhat reduced by the pressure of the water thus tending to rise in it, will still remain a substantial volume acting in the nature of a sponson on such side of the ship and affording increased buoyancy to this side of the ship as it is depressed in the water. When the ship tends to roll in the opposite direction in reaction to the roll thus produced, the side tending to roll out of the water will be resisted in such tendency by the volume of water trapped in its corresponding chamber 18 and from which the outward flow will be resisted by a reduction in pressure of the air in the upper part of the chamber, producing a negative pressure acting over the cross-sectional area of the chamber tending to draw it downwardly. Similarly a positive pressure will be produced in the chamber 18 on the opposite side of the ship also resisting the roll. Thus the water tending to flow out of one chamber and the added buoyancy and pressure provided by the air in the other chamber cooperate to resist the rolling movement of the ship and serve to materially reduce such rolling movement. This serves as an effective damping means on the rolling motions of a ship, these being the movements which are both disagreeable to the passengers and the crews of a ship, and at the same time it minimizes the danger of capsizing of a ship in unusually heavy seas.

Having thus described my invention, what I claim by Letters Patent is:

1. A ship's hull having a chamber extending along each side thereof over the major proportion of the length thereof and extending from a point above the water line thereof to a point adjacent the bottom thereof, said chambers being sealed

5 against the escape of fluid therefrom except adjacent the lower edges thereof and being in open communication with the water adjacent such lower edges, and a longitudinally extending wall in the lower part of each said chamber intermediate the inner and outer walls thereof and fixed with respect thereto.

10 2. A ship's hull having a chamber extending along each side thereof over the major proportion of the length thereof and extending from a point above the water line thereof to a point adjacent the bottom thereof, said chambers being sealed

15 against the escape of fluid therefrom except adjacent the lower edges thereof and being in open communication with the water adjacent such lower edges, and a longitudinally extending wall in the lower part of each said chamber intermediate the inner and outer walls thereof and terminating short of the upper edge thereof, the last-mentioned wall being fixed with respect to said hull.

20 3. In a ship's hull, in combination, a wall arranged in outwardly spaced relation with respect to each side of said ship over a major portion of the length thereof, the upper and forward ends of said walls being sealed to said ship whereby to form a chamber between each of said walls and the corresponding side of said ship, the lower edges of said chambers being open to the water, a plurality of vertically directed bulkheads arranged in longitudinally spaced relation with respect to each other sealed to each of said walls and the corresponding side of said ship whereby to provide a plurality of chambers over the length 25 of each of said walls each sealed with respect to its adjacent chamber except at its lower end, said bulkheads being so constructed and arranged as to flex under the forces tending to move said walls outwardly or inwardly with respect to the corresponding sides of said hull whereby to reduce the strain of such movement on said walls and sides.

30 4. In a ship's hull, in combination, a wall arranged in outwardly spaced relation with respect to each side of said ship over a major portion of the length thereof, the upper and forward ends of said walls being sealed to said ship whereby to form a chamber between each of said walls and the corresponding side of said ship, the lower edges of said chambers being open to the water, a plurality of vertically directed bulkheads arranged in longitudinally spaced relation with respect to each other sealed to each of said walls and the corresponding side of said ship whereby to provide a plurality of chambers over the length 35 of each of said walls each sealed with respect to its adjacent chamber except at its lower end, such bulkheads comprising plates each directed at an angle of less than 90° with respect to the plane of that portion of the side of the ship to which it is secured and all inclined in the same direction.

GEORGE R. HARRISON.
